(57) CLAIM

The ornamental design for a bottle, as shown and described.

DESCRIPTION

FIG. 1 is a rear perspective view of a bottle according to our new and ornamental design;

FIG. 2 is a rear view thereof;

FIG. 3 is a front view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof, showing the bottle pump in an alternative position.

The dashed broken lines showing a suction tube, threads on the suction tube, and an indented portion on the bottom of the bottle are directed to environment and are for illustrative purposes only. The dash-dot broken lines offset immediately inwardly from the bottom edge of the bottle and shown in FIGS. 1 and 6-8 represent the boundary of the claim within the bottom surface. The broken lines form no part of the claim. The appearance of any portion of the bottle between the two break lines forms no part of the claim.
